UNITED STATES PATENT OFFICE.

JOHN ANDAY VIRTUE, OF DELPHOS, KANSAS.

STEAM-ENGINE.

SPECIFICATION forming part of Letters Patent No. 695,510, dated March 18, 1902.

Application filed April 22, 1901. Serial No. 56,812. (No model.)

To all whom it may concern:

Be it known that I, JOHN ANDAY VIRTUE, a citizen of the United States, and a resident of Delphos, in the county of Ottawa and State 5 of Kansas, have invented new and useful Improvements in Steam-Engines, of which the following is a specification.

My invention relates to condensing steam-engines; and the object of my invention is to 10 greatly increase the efficiency or economy of the engine by providing improved means for obviating "back pressure" against the piston. I attain this object by excluding the air from the exhaust-pipe of the engine; and to 15 this end my invention consists in the novel construction and arrangement of parts, which will be hereinafter described and then claimed, reference being made to the accompanying drawings, in which—

20 Figure 1 is a top plan view, partly in section, of an engine constructed in accordance with my invention, the cylinder valve-chest and condensing-cylinder being sectioned on the line *a b* of Fig. 2. Fig. 2 is a sectional view of the cylinders, taken on the line *c d* of Fig. 1, also showing diagrammatically the connection between the cylinder and the steam-boiler, the throttle-valve being omitted.

25 I provide the usual piston-cylinder 2, mounted on the bed-plate 3. Secured to the piston-rod 4 are two piston-heads 5, at about the same distance apart as the stroke of the piston-rod. The inlet-ports 7 are controlled by a slide-valve 8 of any preferred type. The 30 condensing-cylinder 9, made in two or more parts secured together at flanges 10, is secured around the central part of the cylinder 2, so as to be air-tight, suitable packing being employed for this purpose. The steam-pipes 12 are branches of the supply-pipe 13, Fig. 2, leading to the boiler 14. The branch pipes 12 are connected to the steam-chest 15 near its ends in order to avoid passing through the condensing-cylinder 9.

35 The exhaust-ports of the piston-cylinder 2 are composed, respectively, of two series of perforations 16 and 16', arranged in ring form and so located that an exhaust occurs when either piston reaches the end of its 40 stroke. These exhaust-ports 16 16' open into

the condensing-chamber formed by the cylinder 9. To cool the exhaust-steam and hasten its condensation, I provide two annular water-pipes 17 opposite the exhaust-ports, respectively. These pipes are secured in position in any suitable manner and their inner sides are provided with fine perforations through which cold water sprays against the exhaust-steam during the operation of the engine. The water is admitted to the perforated pipes 17 by two risers 18, connected by a lateral pipe (not shown) connected to a supply-pipe 19.

A drain-pipe 20 is connected to some point at the bottom of the condensing-cylinder 9. 55 This drain-pipe leads preferably to a tank 21, and from the lower part of the tank a pipe leads to an injector, (indicated at 22,) which injector is also connected to the boiler of the engine in the usual manner. The hot water 60 condensed from the steam in cylinder 2 escapes through pipe 20 into the tank, in which it partially cools. The injector is operated continuously in order to relieve the pistons 5 of any back pressure. The tank 21 may be 65 dispensed with if an injector is employed which will feed hot water as well as cold.

I connect a blow-off cock 23 to some convenient part of the condensing-drum 9 in order that when the engine is started this 80 cock may be opened for a few seconds or long enough to permit the air which may have entered said drum through the piston-cylinder to be displaced by the exhaust-steam. The cock 23 is then closed.

While the drawings represent the preferred form of my invention, certain modifications of detail or arrangement of parts may be resorted to without departing from the scope of my invention.

Having now fully described my invention, what I claim as new, and desire to secure by Letters Patent of the United States, is—

In a steam-engine, a piston-cylinder; two sets of exhaust-ports in said cylinder; each 95 set comprising a series of openings arranged in a ring around said cylinder; a condensing-drum secured air-tightly around said cylinder, or around that portion thereof containing said exhaust-ports; annular water-pipes 100

2
arranged around said exhaust-ports, within said condensing-drum, said pipes having inwardly-directed perforations for spraying water toward said exhaust-ports; and a supply-
5 pipe connected to said annular perforated pipes for supplying them with cold water, substantially as described.

In testimony whereof I affix my signature in the presence of two witnesses.

JOHN ANDAY VIRTUE.

Witnesses:

M. J. ROBERTSON,
FRANK BURNS.
